DESIGN FOR A MUSICAL WIND INSTRUMENT

Julius Hommer, Union, N. J.

Application January 31, 1942, Serial No. 105,543

Term of patent 3½ years

To all whom it may concern:

Be it known that I, Julius Hommer, a citizen of the United States and residing at Union, in the county of Union and State of New Jersey, have invented a new, original, and ornamental Design for a Musical Wind Instrument, of which the following is a specification, reference being had to the accompanying drawing, forming part thereof, and in which:

Fig. 1 is a top plan view of a musical wind instrument, showing my new design;

Fig. 2 is a side elevational view; and

Fig. 3 is an end elevational view.

I claim:

The ornamental design for a musical wind instrument, substantially as shown.

JULIUS HOMMER.
